UNITED STATES PATENT OFFICE.

EDWARD MUIR, OF SPRINGFIELD, ILLINOIS.

GUARD-RAIL APPLIANCE FOR RAILROADS.

No. 892,869.

Specification of Letters Patent.

Patented July 7, 1908.

Application filed September 17, 1907. Serial No. 393,419.

To all whom it may concern:

Be it known that I, EDWARD MUIR, a citizen of the United States, and a resident of Springfield, in the county of Sangamon and State of Illinois, have invented certain new and useful Details of Construction for Guard-Rail Appliances for Railroads, of which the following is a full, clear, and exact description.

10 Ordinarily, the guard rail where applied, is secured in place by means of spikes that engage the guard rail, and are driven into cross ties whereon the guard rail is seated. This method of securing a guard rail frequently proves to be unreliable for several causes; and in consequence, serious accidents have occurred.

One object of this invention is to provide a filling block of novel form for spacing the 20 guard rail from an adjacent track rail at and near each end of the guard rail, said filling blocks also serving as foot guards; and a further object is to provide a clamp of novel form, which coacts with the improved filling 25 block for retaining said block in operative position between a main track rail and a guard rail.

The invention consists in the novel construction and combination of parts, as is 30 hereinafter described and defined in the appended claims.

Reference is to be had to the accompanying drawings forming a part of this specification, in which similar characters of reference 35 indicate corresponding parts in all the views.

Figure 1 is a plan view of a supported track rail in part, a guard rail, and the improved appliances applied for holding the guard rail in position; Fig. 2 is an enlarged transverse 40 sectional view, substantially on the line 2—2 in Fig. 1; Fig. 3 is a side view of a guard rail and of a novel detail connected therewith, and Fig. 4 is an enlarged transverse sectional view, substantially on the line 4—4 in Fig. 1.

45 In the drawings that represent a practical embodiment of the invention, 5 indicates a railroad track rail, and 6, cross ties whereon the track rail is seated and secured by spikes a. A guard rail 7, formed of track rail material, similar in form considered transversely, to the track rail 5, is placed upon the cross ties 6 at a suitable point opposite and near to the track rail 5 and secured thereto by spikes a'.

55 One essential detail of the invention con-

sists of a filling block 8 which in duplicate, is located between the track rail 5 and guard rail 7 at the ends of the latter.

As represented in Fig. 1, the end portions 7^a of the guard rail 7 are bent laterally at 60 equal degrees, thus causing the extremities of the guard rail to diverge from the side of the main track rail and afford an entrance throat thereat as usual. The spaces between the track rail 5 and guard rail 7, at each end 65 of the latter, if not filled up to the balls of the track rail and guard rail, are liable to catch and hold the foot of an unwary person traversing the railroad track. One feature of the filling block 8, for each end of the guard 70 rail 7, consists in such a formation of its body as adapts it to fit closely in the converged space between the track rail 5 and guard rail 7, as is clearly shown in Figs. 1 and 2.

In Fig. 2, the upper surface b of the filling 75 block 8 is shown concaved between the track rail 5 and guard rail 7, while the sides and portions of the top surface thereof fit respectively in bearing contact upon the webs and lower surfaces of the balls of the rails. It 80 will also be noted that the lower surface of the filling block 8 is shaped so as to be seated upon the adjacent base flanges of the track rail and guard rail; furthermore, the height of the filling block, at its inner end, is so proportioned that the heads or balls of the rails 5, 7, only extend above the concavity b, which will effectively prevent one's feet from wedging immovably between these rails at 85 their points of closest approach to each other. 90

As usual, the guard rail 7 is secured upon the cross ties 6 by spikes a', as before mentioned, and as a special means for holding the guard rail in position thereon, a pair of novel clamps are provided. Each clamp consists 95 of a preferably malleable metal body 9 formed with a central transverse recess c therein, that is undercut along each side at the junction thereof with the bottom, thus producing two opposed channels c' wherein, 100 the outer base flanges of the track rail 5 and guard rail 7 are embedded, as shown in Fig. 2. The clamping block 9, on the side of the recess c in each one that is above the undercut channel c', bears upon the outer surface of the 105 web of a track rail and guard rail respectively, when the blocks are placed in position.

Each filling block 8 is sloped outward and downward on its concave upper surface from the inner portion, which is of least width, to 110

the outer end b' thereof, thus affording a gradual upward trend to said concaved surface b , as shown in Fig. 4, which adapts car wheels and the like to traverse the track rail 5 at the guard rail, without jar. Each clamp employed, embraces the webs of the track rail 5 and guard rail 7, where the narrow end portion of a respective filling block 8 is introduced between the webs of said rails that are parallel at said points; and for holding the filling blocks in enforced engagement with the webs of the track rail and guard rail, the clamping blocks, rail webs and intervening ends of the filling blocks are transversely 10 per- 15 forated, said holes receiving bolts d which are held in place by nuts d' . Preferably the holes in the clamping blocks 9 and the filling blocks 8 are cast therein by use of cores, said parts being formed of cast steel or iron as 20 may be preferred.

It will be seen that by the described construction and arrangement of parts, a guard rail support and attachment, which is novel, very simple, durable, absolutely safe, and 25 convenient to place or remove, is provided at a comparatively low cost.

In assembling the device, the brake rail being in place, the clamp blocks 9, are positioned on the track rail, after which the 30 guard rail 7 is positioned in the clamps. The filling blocks b are now inserted and the bolts

d passed through the alined opening and secured in place by the nuts d' .

Having thus described my invention, I claim as new and desire to secure by Letters 35 Patent:

The combination with a track rail and a guard rail diverging at each end from the track rail, of a wedge-shaped filling block fitted between the ends of the guard rail and the track rail, said block having a portion with one inclined side for engaging between the track rail and the diverging portion of the guard rail, and a portion with parallel sides for engaging between the parallel portions of the guard rail and the track rail, the filling blocks having concaved upper surfaces inclined downwardly toward the outer ends thereof, and clamps having a recess on the upper face for receiving the track rail, the guard rail; and the filling block, said recess being undercut to receive the rail bases, and a bolt traversing the rails and the filling blocks.

In testimony whereof I have signed my 55 name to this specification in the presence of two subscribing witnesses.

EDWARD MUIR.
